UNITED STATES PATENT OFFICE.

FRANKLIN L. BARBER, OF CHICAGO, ILLINOIS, ASSIGNOR TO STANDARD CAR TRUCK COMPANY, OF CHICAGO, ILLINOIS, A CORPORATION OF NEW JERSEY.

ROLLER SIDE BEARING.

1,396,014.

Specification of Letters Patent.

Patented Nov. 8, 1921.

Application filed November 22, 1920. Serial No. 425,660.

To all whom it may concern:

Be it known that I, FRANKLIN L. BARBER, a citizen of the United States, residing at Chicago, in the county of Cook and State of Illinois, have invented certain new and useful Improvements in Roller Side Bearings; and I do hereby declare the following to be a full, clear, and exact description of the invention, such as will enable others skilled in the art to which it appertains to make and use the same.

This invention relates to a roller bearing and particularly to a side bearing for railway cars, which bearing is adapted to be carried by the body bolster of the car to bear upon the wearing surface of the truck bolster.

It is an object of this invention to provide such a bearing of rugged construction, few and simple parts, and one which will automatically tend to resume and maintain its normal position.

This, and other objects and advantages of the invention will appear as the description proceeds in connection with the accompanying drawings, in which like reference characters refer to the same parts throughout the different views, and in which,

Figure 1 is a view in side elevation of the bearing;

Fig. 2 is a partial bottom plan view thereof; and

Fig. 3 is a view in elevation of the device as seen from the right of Fig. 1, a portion of the device being shown in section.

Referring to the drawings, the device comprises a supporting member 1 shown as provided with a base flange having four diverging and symmetrically arranged lugs 2. Each of these lugs is provided with a raised finishing boss through which pass the holes 3 adapted to receive securing bolts or screws. The said flange is formed on an incline, or with a batter, as clearly shown in Fig. 3, to conform to the shape of the car body bolster. Depending from the base flange of member 1 and spaced therefrom is a second flange member 4. This flange extends across the ends of the member 1, as shown in Figs. 2 and 3, and is of the same conformation as the flange 5 which is arranged to contact therewith and be secured thereto by the nutted bolts 6. The flange 5 is carried by a housing member 7 having a base of general rectangular shape adapted to be received within the

depending flanges 8 of member 1. The member 7 also has depending parallel sides and curved end portions which are clearly seen as 9 in Fig. 1. An elongated horizontally disposed opening 10 is formed in the said depending side portions of the member 7, which opening is shown as surrounded by a strengthening rib 11. The member 7 has portions 7^a projecting at each side thereof, which are received in the recesses formed by flanges 8, and these projections are formed along their lower edge at the outer portion thereof, with rack teeth 12. The member 1 is also formed with a central rectangular recess adapted to receive a rectangular wear-ing plate 13.

A central bearing pin 14 passes transversely through the openings 10 in the sides of member 7 and has disposed thereon at each side of said member the counterweight members 15. Pin 14 is headed at one end and suitably threaded at the other to receive a nut and washer to hold the members 15 in proper position. The pin 14 also passes through a central opening in a roller member 16 which is disposed between the sides of the member 7 and which has cylindrical projections 17 at each end thereof arranged to be received in the elongated slots or openings 10. The counterweight members 15 have openings of larger diameter than the pin 14 to loosely engage the same and are formed below said pin with an enlarged counterweight portion 15^a, and above said pin are formed as a gear quadrant having the radial teeth 15^b. These teeth as shown in Figs. 1 and 3 are arranged to engage with the rack teeth 12 carried by member 7. It will be noted that the roller member 16 is arranged to bear at its upper side against the surface of plate 13, and at its lower side, said roller projects beyond the member 7 and is designed to bear upon the wearing surface of the truck bolster. The roller member 16 is cored or bored to loosely fit the pin 14.

When relative motion occurs between the body bolster and truck bolster, as when the car is going around a curve, the roller member will be traversed along the bearing surfaces and the counterweight member 15 will be swung into an angular position relative to that shown in Fig. 1, by the engagement of the gear teeth thereon with the rack teeth on member 7, said member swinging about the axis of pin 14. When the bearing sur-

100

105

110

face is again moved to resume normal position, the counterweight member 15 will tend to descend by gravity and the roller member will thus be assisted in returning to its normal central position.

It will be noted that a slot or channel is formed at one side of the central inside portion of member 7, as shown at 7^b in Fig. 3, which is also indicated by dotted lines in Figs. 1 and 2. When the device is assembled, the roller member 16 will be dropped into the housing 7 by letting the end projection 17 thereon pass through this slot. The pin 14 is then passed through the counterweight member through the roller and through the other counterweight member.

It will thus be seen that applicants have produced a simple and efficient roller side bearing, parts of which are rugged in construction, are such as to be easily assembled, and when so assembled, will require little attention. The invention, generally stated, consists in the matter shown and described and set forth in the appended claims.

What is claimed is:

1. A side bearing adapted to be carried by the body bolster of a car having in combination means adapted to engage said bolster and to be secured thereto, a housing depending from said means, a bearing roller disposed in said housing and carrying an axle member projecting at either side of said housing, counterweight members mounted on said axle members on each side of the housing, and means on said housing above said axle member for engaging said counterweight member whereby when the roller is moved longitudinally the counterweight will be swung out of its normal position.

2. A side bearing for a railway car having in combination a base member adapted to be secured to the body bolster of said car, a housing depending therefrom having parallel sides, a bearing roller disposed in said housing and carrying an axle member projecting at each side of said housing, counterweight members loosely mounted upon said axle member at each side of said housing closely adjacent thereto, a rack carried by

said housing above the counterweight member, said counterweight member having a gear quadrant formed thereon above said axle member engaging with said rack whereby when the roller is moved the counterweight member will be swung into an angular abnormal position.

3. A side bearing for a railway car having a base member adapted to be secured to the body bolster of a car, a housing member depending therefrom having parallel sides, said sides having elongated horizontal openings therein, a bearing roller disposed between the sides of said housing having cylindrical projections at its ends disposed in said elongated horizontal openings, an axle member carried by said roller projecting through said openings at each side of the housing, counterweight members mounted on said axle member at each side of the housing with the counterweight portion thereof below said axle member, a rack carried at each side of the housing member above said counterweight members, gear teeth on said counterweight members above said axle member engaging with said racks.

4. A side bearing for a railway car having in combination a base member adapted to be secured to the body bolster of a car, said base member having a recess formed in its upper portion, a bearing plate disposed in said recess, a housing depending from said base member, a roller disposed in said housing and engaging said bearing plate, a bolt passing centrally through said roller and projecting beyond the sides of said housing, counterweight members mounted upon said bolt at each side of said housing, and means on said housing disposed above said bolt to engage said counterweight member whereby said member will be swung angularly upon movement of said roller.

In testimony whereof I affix my signature in presence of two witnesses.

FRANKLIN L. BARBER.
